MACHINE FOR BEVELING SOLES

Eugene J. Ray, Beverly, Mass., assignor to United
Shoe Machinery Corporation, Flemington, N. J.,
a corporation of New Jersey

Application February 10, 1947, Serial No. 727,703

3 Claims. (Cl. 69—9)

1

This invention relates to rotary cutterheads and machines equipped with them. It is concerned specifically with a problem involved in beveling unattached shoe soles.

For example, an outsole intended to be attached with cement to a woman's shoe is usually prepared as follows: after it has been cut approximately to the desired final outline the marginal bands of its attaching face are shaved in the shank portion to make them thinner than the marginal band in the forepart; and thereafter the marginal bands in both the shank and the forepart are coated with sole-attaching cement which is permitted to harden prior to attaching the sole. After the sole has been attached to a shoe it must undergo a final edge-trimming operation, edge-inking or staining, and edge-setting, but satisfactory results in these operations cannot be obtained if the marginal extension of the sole is coated with cement.

To remove a narrow outer band of the relatively wide band of hardened cement prior to assembling the sole with a shoe, the present invention provides a beveling machine in which a rotary cutter-head is telescopically related to an upright driving shaft and adapted to "float" independently thereof. The cutter-head includes two collars, one of which is arranged to ride on the upper face of the margin of a sole and thereby float the cutter, and the other arranged to run on the perimeter of the sole and thus serve as an edge-gage. The freedom of the cutter-head to float without being loaded with the weight and inertia of the shaft, a pulley and a driving belt insures a bevel of the same width in the forepart of a sole as in the shank, despite greater thickness of the forepart.

Referring to the drawings,

Fig. 1 is a top plan view of a portion of a machine embodying the invention;

Fig. 2 is a vertical section through the cutter-head assembled with a shaft of one well-known type;

Fig. 3 is a cross-section indicated by line III—III in Fig 2;

Fig. 4 is a vertical section of the cutter-head assembled with a shaft of another type;

Fig. 5 is an elevation of the cutter; and

Fig. 6 is an elevation of the adapter included in Fig. 4.

The cutter comprises a cylindrical hub 10 and a circular series of cutting teeth 11 projecting from the periphery thereof, the tips of the teeth being beveled to provide inclined cutting edges 12. The hub extends above and below the teeth

2

11, the portion above the teeth providing anchorage for a collar 13, and the portion below them providing anchorage for a collar 14. Two diametrically opposite segments 15 of one end of the hub are formed by cutting away two other segments, the segments 15 constituting clutch elements by which the cutter may be driven.

The collar 13 is fastened to the hub 10 by a set-screw 16, its lower face lying on the teeth 11 and projecting radially beyond them to ride on the upper face of the margin of a sole 17 and thereby float or support the cutter in the desired relation to the sole. This collar is provided with small holes 18, one for each tooth 11, through which dust and small chips of sole stock may escape from the teeth.

The collar 14 is fastened to the hub by a set-screw 19. Its circular periphery is arranged to guide the perimeter of the sole.

20 Fig. 2 illustrates one well-known type of cutter shaft 20 having an integral cylindrical end portion 21 of a size to fit the bore of the hub of the cutter and to be telescopically related thereto. A larger portion of the shaft, adjoining the 25 inner end of the portion 21, is provided with two diametrically opposite grooves to receive the segments 15 of the hub 10 (Fig. 3) and to form driving segments 22 with which the segments 15 may be interengaged.

30 Fig. 4 illustrates another type of cutter shaft which comprises a body section 20' and a non-expansive sleeve section 21'. These are tightly connected by a screw 23' and a retaining washer 24' which abuts the outer end of the sleeve section and projects radially therefrom to provide a shoulder. The body section has a conical portion 25' primarily intended to carry an expandable sleeve and a cutter or other tool, but which, for purposes of the present invention, is nested in the non-expansive sleeve section 21' and engages its interior surface to maintain it in coaxial relation to the body section. The sleeve section 21' fits the bore of the cutter and is utilized as

35 a 40 adapter to which the cutter may be telescopically related with the same effect as it would have if mounted as shown in Fig. 2. The inner end of the sleeve section is provided with driving segments 22' (Fig. 6) arranged to be interengaged with the segments 15 of the cutter.

45 Fig. 1 represents a top plan view of a portion of a machine comprising a horizontal work-supporting table 30, a power-driven feed-wheel 31 and a power-driven shaft and cutter assemblage arranged to rotate about an upright axis. The 50 cutter shaft may be either type shown in Figs. 2

and 4. The table 30 is fixed to remain at a constant level, but the feed-wheel 31, which runs on the upper face of a sole 17, is movable up and down according to variations in the thickness of the sole. The feed-wheel is affixed to a driven shaft 32, and the latter is journaled in a yieldable bearing member 33 that is spring-biased downwardly to maintain pressure of the wheel upon the sole. The periphery of the feed-wheel comprises teeth having sharp outcurved edges for engaging the work.

The feed-wheel is driven in a direction to feed a sole toward the cutter assemblage which is initially supported by the driving segments 22 (or 22', as the case may be) of the cutter shaft. The latter is supported at a constant level by its bearings (Fig. 4) in a frame 34, and is driven in the direction indicated by an arrow in Fig. 1.

The table 30 is set at a level that will enable the cutting edges 12 to bevel the margin of a sole at its thinnest points, usually in the shank. In Fig. 1 the lines 35 represent the inner boundaries of areas that have been reduced to less thickness than the margin of the forepart. The line 36 represents the inner boundary of a narrow marginal band that has been beveled by the edges 12.

When a beveling operation is begun by sliding a margin of the heel seat of a sole under the feed-wheel 31, the latter feeds the sole under the collar 13, under the inclined cutting edges 12, and against a fixed guide 37 and the collar 14. No manual control of the sole is necessary or desirable after the feed-wheel has once taken hold of it. Although the primary component of feeding force derived from the feed-wheel is from left to right, the cutting edges 12, and, to a lesser extent, the collars 13 and 14, furnish a secondary component in a direction oblique with respect to that of the primary component. The feed wheel, the fixed guide 37 and the collar 14 are so related as to maintain the sole in a true relation to the cutter throughout a beveling operation and to turn the sole end for end as the operation progresses around the toe end thereof.

As the beveling progresses from a margin of the shank to a thicker margin of the forepart, the cutter-head will slide up relatively to its shaft, and when the beveling passes from the forepart to the thinner margin of the shank the cutter-head will slide down accordingly, and thereby maintain uniform width of the beveled band. These sliding movements of the cutter-head are governed by the rim of the collar 13 which projects outside the orbit of the teeth 11 and rides on the upper surface of the work.

The weight of the cutter-head would, in some circumstances, be sufficient to maintain the collar 13 in contact with the work, but when the cutter is to be used to remove a narrow band of hardened sole-attaching cement from the upper surface of a leather sole it is preferable to provide a compression spring 26 to bias the cutter-head toward the inner end of the cylindrical portion 21, or the sleeve section 21', as the case may be. In the assemblage shown in Fig. 2 the spring surrounds the portion 21 between the hub 10 and the projecting rim of a retaining washer 24 which is fastened to the end of the shaft by a screw 23. In the other assemblage (Fig. 4) the spring surrounds the sleeve section 21' between the hub

10 and the rim of the retaining washer 24'. The axial dimensions of the interengaged segments of the shaft and the cutter are long enough to maintain the driving connection when the collar 13 is riding on the thickest part of a sole.

Having described the invention, what I claim as new and desire to secure by Letters Patent of the United States is:

1. In a machine for beveling unattached soles, a work-supporting table, a rotating supporting means arranged to rotate about an upright axis, a cutter surrounding said rotating supporting means in telescopic relation thereto and arranged to slide up and down with respect thereto, the cutter having peripheral cutting teeth above the plane of the table and a hub extending above and below said teeth, a collar affixed to said hub above said teeth and extending radially beyond them to ride on the upper face of a sole and thereby support the cutter, and another collar carried by said hub below said teeth to guide the perimeter of the sole, said rotating supporting means and said hub having interengaged elements arranged to drive the cutter and permit it to slide up and down in response to variations in the thickness of the margin of the sole.

2. A rotary cutter assemblage comprising a shaft having a cylindrical end portion, a cutter having a hub and peripheral cutting teeth, said hub surrounding said cylindrical end portion in telescopic relation thereto, a retaining member detachably fastened to the shaft beyond the outer end of the cutter, and a compression spring surrounding the shaft between said retaining member and the cutter to bias the latter inwardly from the retaining member, the shaft and the inner end of said hub having interengaged segments for driving the cutter.

3. A rotary cutter assemblage comprising a shaft including a body section and a detachable sleeve section, the sleeve section having a cylindrical periphery and the body section having a portion nested in the sleeve section and engaging the interior surface thereof to maintain concentric relation of the sections, means detachably connected to the body section for fastening the sleeve section tightly thereto, said means including a retaining member abutting the outer end of the sleeve section and projecting radially therefrom to provide a shoulder, a cutter surrounding said sleeve section in telescopic relation thereto, said cutter having a hub and peripheral cutting teeth, and a compression spring surrounding the sleeve section between said shoulder and the cutter to bias the latter toward the inner end of the sleeve section, said hub and the sleeve section having interengaged segments arranged to drive the cutter and permit endwise movement thereof.
